UNITED STATES PATENT OFFICE

2,506,541

SINK TOP CONSTRUCTION

James M. Callaghan, Chicago, Ill.

Application September 7, 1945, Serial No. 614,848

3 Claims. (Cl. 4—187)

1

The invention relates to sink top construction. One object of the invention is to provide an improved sink top construction which facilitates the installation of a top-liner.

Another object of the invention is to provide a sink top construction which includes a pre-formed frame which has a contour conforming to and fitting on the rim of the sink and a mat secured to the frame to form a unit which can be easily installed on the sink for the laying of a top-liner of linoleum, over the structural top around the sink.

Other objects of the invention will appear from the detailed description.

The invention consists in the several features hereinafter set forth and more particularly defined by claims at the conclusion hereof.

In the drawings:

Fig. 1 is a perspective of a sink-top embodying the invention, parts shown in section for illustrative purposes.

Fig. 2 is a vertical section taken on line 2—2 of Fig. 1, through the sink, the frame, and mat mounted on the base with the top liner of linoleum installed thereon.

Fig. 3 is a detail perspective of the frame.

Fig. 4 is a perspective of the mat which is secured to the frame.

The invention is exemplified as applied to a sink-bowl 10 which is provided with an outwardly projecting continuous flange forming a rim 11, the margin of which fits in an opening in a structural top 14 which is usually formed of wood and serves as a shelf or drainboard for use with the sink.

The invention comprises a frame, generally designated 16, which corresponds in contour to the top rim of the sink-bowl 10 and includes a laterally extending flange 17 adapted to overlie the rim 11 of the bowl and an integral upstanding flange 18, the inner face of which is downwardly convergent or curved to its meeting line with the sink. The frame 16 extends continuously around and over rim 11 and is preferably formed of metal. The inner face of flange 18 which is exposed, is usually provided with a finish, such as chromium or nickel plate for appearance.

A mat 19 has an opening 20 therein with its margin conforming to and fitting around the outer face of flange 18. The bottom face of the mat fits on the top of flange 17 and is permanently secured thereto, for example, by rivets 24. The outer margin of mat 19 projects laterally beyond the flange 17 of frame 16 into overlapping relation with and supports said frame on the struc-

tural top 14. This frame with mat attached thereto constitutes a prefabricated unit which fits over the rim on bowl 10 and overlaps and is supported by the structural top 14 for supporting a top-liner 25 of material, such as linoleum, around the bowl. The upstanding flange 18 is of sufficient height so it will be flush with the top face of the linoleum when the latter is laid on the mat 19. This mat may be formed and cut of any suitable sheet material, such as pulp board or material commercially known as "Masonite." In installing the linoleum liner 25, it is only necessary to cut an opening therein conforming to face 23 of the upstanding flange 18. A filler layer 27 of suitable sheet material, such as "Masonite" is laid on the structural-top 14 and has a thickness corresponding to the thickness of the mat 19 so that the mat and layer will provide a flush surface on which the linoleum may be laid and cemented. A metal molding for providing a trim or finish for the front edge of the structural-top 14 and the linoleum top 25 comprises a vertical flange 30 and a horizontal flange 31 which is co-planar with the mat 19.

25 In the use of the invention, the frame and mat are preferably prefabricated as a unit to fit the rims of sink-bowls of standard sizes. When it is desired to install on the structural top a top-liner of linoleum, the assembled frame 16 and mat 19 are placed on the top of the rim 11 of bowl 10 and the top-face of the structural top 14. The filler layer 27 is then laid on the structural top 14 so that it will be flush with the top face of mat 19. An opening is then cut in the linoleum to conform to the face 23 of flange 18 of the frame 16. The linoleum is then laid on the mat 19 on the filler layer 27 and cemented thereto. The upper edge of flange 18 of frame 16 will be substantially flush with the top face of the linoleum so that the liner 25 and frame 16 will present a finished appearance. By prefabricating the frame with the mat, the installation of the linoleum liner is greatly expedited.

30 40 45 The invention exemplifies a sink-top construction which can be readily installed over the structural top and the rim of a sink-bowl without requiring skilled work. The invention also provides a single frame which forms an edge trim for the linoleum around the bowl and conforms to the contour of the bowl for attractiveness in appearance.

The invention is not to be understood as limited to the details described, since these may be modified within the scope of the appended claims with-

out departing from the spirit and scope of the invention.

Having thus described the invention, what I claim as new and desire to secure by Letters Patent is:

1. A top construction for a sink provided with a rim, comprising a one-piece frame and a surrounding mat, pre-assembled for unitary placement on the sink, the frame having contour corresponding to, and overlying the rim of the sink, and being provided with integral upstanding and outwardly extending flanges, the mat fitting around the upstanding flange, and projecting outwardly from the laterally extending flange for overlying a portion of a structural top around the sink and providing a surface for supporting a top-liner of linoleum or the like, around the upstanding flange.

2. A top construction for a sink provided with a rim, comprising a one-piece frame and a surrounding mat, pre-assembled for unitary placement on the sink, the frame having contour corresponding to, and overlying the rim of the sink and being provided with integral upstanding and outwardly extending flanges, the mat fitting around the upstanding flange, being fixed to and projecting outwardly from the laterally extending flange, for overlying a portion of a structural top around the sink and providing a surface for supporting a top-liner of linoleum or the like, around the upstanding flange.

3. A top construction for a sink provided with a rim, comprising a pre-assembled one-piece frame and a surrounding mat, pre-assembled for unitary placement on the sink, the frame having contour corresponding to, and overlying the rim of the sink, and being provided with an integral upstanding flange having a vertical outer face and outwardly extending flange, the mat fitting around the upstanding flange and projecting outwardly from the laterally extending flange for overlying a portion of a structural top around the sink and providing a surface for supporting a top-liner of linoleum or the like, around the upstanding flange, the outer face of the vertical flange adapting the top-liner to be laid from above, onto the mat and around the upstanding flange with the upper edge of the upstanding flange substantially flush with the top-face of the top-liner.
